UNITED STATES PATENT OFFICE.

JOSÉ CORDEIRO FERREIRA ROQUETTE, OF PARIS, FRANCE, ASSIGNOR TO MANOEL DE ORTIGAO BURNAY, OF PARIS, FRANCE.

THERMOSTATIC CIRCUIT CLOSER.

Application filed June 17, 1921. Serial No. 478,336.

To all whom it may concern:

Be it known that I, José CORDEIRO FERREIRA ROQUETTE, citizen of the Republic of Portugal, residing at 139 Boulevard Péreire, Paris, France, have invented certain new and useful Improvement in Thermostatic Circuit Closers, of which the following is a specification, reference being had therein to the accompanying drawing.

- 10 Fire alarm signals have been heretofore proposed, in which the air expanding under the action of the heat causes closing of an electric circuit connected to the signal apparatus proper, such as an audible alarm.
- 15 The present invention relates to an arrangement of the foregoing type, and is characterized by the fact that the dilatable chamber communicating with the air expansion chamber is provided on its extensible wall with an air escape orifice opposite a regulating member, such as a pointed screw, and opening freely to atmosphere, the construction being such that the orifice closes progressively when the extensible walls of the dilatable chamber approach the regulating member under the action of the increased pressure of the heated air.

A representative embodiment of the invention is illustrated by the way of example on the accompanying drawing, in which:

Fig. 1 is a vertical section of the apparatus,
Fig. 2 is a plan, and
Fig. 3 is a horizontal section on the line 35 3—3 of Fig. 1.

Fig. 4 is a vertical section on a larger scale showing the air vent.

Fig. 5 is a vertical section, also on the larger scale, showing the attachment of the electric terminal to one of the supports of the apparatus.

The apparatus consists of an air expansion chamber, a dilatable chamber and a frame supporting these two chambers.

45 The air expansion chamber 1 is provided between a sheet metal cylinder 2 and a sheet metal cylinder 3, having large corrugations 4; these cylinders being with advantage built up of very thin good heat conducting material yet having as small a coefficient of expansion as possible.

The chamber 1 is closed on top by an annular disc 5. The cylinder 2 is closed at the

base by a circular bottom 6 and the cylinder 3, having the corrugated periphery, by an annular disc 7, providing between them a free space 8, freely communicating on the one hand with the air expansion chamber 1 and on the other hand, by a passage 9, with the dilatable chamber 10.

The dilatable chamber 10 has a base 11 constituted by a corrugated yielding diaphragm, like the diaphragms of the chambers of aneroid barometers, and provided with an air vent 12.

This air vent is constituted as follows: A socket 13 (Fig. 4) is secured to the base 11 of the dilatable chamber and communicates therewith by an orifice 14. A washer 15 perforated centrally is screwed on the socket 13. A choking substance of any kind, cotton wool for instance, is located at 16 within the socket 13.

A pointed adjustable screw 18, mounted on the frame of the apparatus, controls the aperture of the washer 15.

A ring 40 of insulating material is interposed between the pointed screw 18 and the plate 26 and insulates these elements one from the other. The conducting wire is secured between the ring 40 and the plate 26.

The frame of the apparatus is built up of uprights 25, four for example, interconnected on the one end by the annular upper plate 5, and on the other end by a circular lower plate 26.

On the circular plate 26 are mounted insulated supporting pillars 27, on which rests the base of the air expansion chamber; one of these pillars carries a blade spring 28, the free end of which is bent towards the corrugated diaphragm 11 of the dilatable chamber 10; this spring can encounter an electric contact 29, mounted on the plate 26.

The plate 26 also carries electric terminals 30 and the pointed screw 18 which controls the aperture of the washer 15.

Each terminal 30 is constituted for example (Fig. 5) by a metal nut 32, screwed on a screw-threaded extension 33 of an upright 25, such metal sleeve and extension being insulated by an insulating socket 34 from the conductive plate 26.

A kind of dome 35 envelopes the lower portion of the apparatus. A wide mesh screen 36 may moreover be secured to the

frame and enclose the entire apparatus above described, thus preventing accidental damage thereof.

The circuit 29, 28, 3, 5, 25, 33, 32 being closed an alarm contrivance such as an electric bell is actuated. As many alarm contrivances may be provided such as bells, as there are terminals 30, or several may be in series with one terminal.

- 10 The above described apparatus acts as follows: If a fire breaks out the heat waves produced come into contact with both the external corrugated surface of the cylinder 3 and with the internal surface of the cylinder 2, which is freely open at the top. The cylinders 2 and 3, of good heat conducting material, become heated, and likewise the air contained in the chamber 1. Such air expands, its pressure increases, as 15 the pointed screw 18 controlling the aperture of the washer 15, and the packed mass of choking material, cotton wool for example, oppose the escape of the air. Under the action of this increase of pressure of 20 the air, the yielding diaphragm 11 of the dilatable chamber 10, dilates, comes into contact with the blade spring 28 and thrusts same downwards. The dilation of the dilatable chamber 10 results also in the washer 25 15 approaching the pointed screw 18 and in consequence reducing more and more the area of the air vent in such washer, the internal air pressure of the chamber 1 then increases and the blade spring 28 becomes 30 more and more downwardly bent and finally 35 encounters with the electric contact 29.

Instead of actuating an electric bell, the

completed electric circuit may open or initiate the opening of the control cock of a fire quenching sprinkler system, or the like.

Normal gradual heating of the apartment in which the apparatus is situated, has no effect thereon, as the expanding air gradually escapes through the vent without dilating the chamber 10.

Claims:

1. In an alarm apparatus of the character described, the combination of a dilatable chamber having an extensible wall provided with an air escape orifice opening to atmosphere, a regulating member mounted on the frame of the apparatus and arranged opposite said orifice, means controlled by the dilatable chamber when the latter expands to close an electric circuit connected to the alarm proper, and an air expansion chamber communicating with the dilatable chamber.

2. A fire alarm apparatus as claimed in claim 1 characterized by two cylindrical walls arranged one within the other, the exterior cylindrical wall presenting large undulations and being closed at its lower part by a plate, the interior cylindrical wall being closed at its lower part by a plate and freely open at its upper part, and an annular plate closing the upper part of the free space between the two walls, said space constituting the air expansion chamber and communicating with the dilatable chamber.

In testimony whereof I have hereunto affixed my signature.

JOSÉ CORDEIRO FERREIRA ROQUETTE.
